SYDNEY E. BENDER, OF BROOKLYN, NEW YORK

SAMPLE COLOR CARD

Application filed June 26, 1931. Serial No. 547,001.

This invention relates to improvements in sample color card books and particularly to such devices employed for colored samples of textile material.

5 This application is in part a continuation of the original case filed by the applicant, and bearing the Serial Number 491,910, and the filing date of October 29, 1930.

One of the objects of this invention is to 10 provide a handy sample color card book, composed of a plurality of individual sections, each section having provisions for removably supporting a plurality of individual tabs, carrying colored yarn samples. The book is 15 so arranged that those individual sections may be folded against one another, so as to form a compact fold or book which may be easily carried, and just as easily unfolded (or folded), either in part or in whole.

20 Another object of my invention is to provide a sample color card book composed of individual sections, each section provided with reinforcements at the longer edges of the sections, and a tab carrier or backing member disposed between the reinforcements of the sections, equipped with means for facilitating the attachment of individual, removable yarn sample carrying tabs.

Another object of my invention is to 25 provide, in combination with such sample color card books, individual color card samples made of an attachable carrier, a yarn sample support secured to that carrier, and a yarn sample secured to said support, said tab having provisions for facilitating its being incorporated with or removed from the backing member of each section, and for limiting the movement of the tab relative to said backing member.

30 The foregoing and still further objects will become more fully evident as the following descriptions of my device proceeds, and from the accompanying drawing, forming part of this specification, not, however, intended to 35 limit my disclosure to the actual designs illustrated, and in which

Figure 1 is a plan view of a portion of one form of an open sample color card book, with the upper faces of the backing members 40 exposed.

Figure 2 is an end view, seen from the bottom, of Figure 1.

Figure 3 is an end view of a folded book, of the construction shown in Figures 1 and 2.

Figure 4 illustrates a modified form of a 55 portion of a section.

Figure 5 is a plan view of a portion of an open sample color card book in a modified arrangement, and illustrating a plurality of sections with their inner or backing member 60 surfaces exposed to view.

Figure 6 illustrates an end view of a partially folded book composed of sections in the arrangement shown in modified form of 65 Figure 5.

Figure 7 illustrates an end elevation of a folded book composed of an arrangement of sections similar to that shown in Figure 5, and

Figure 8 illustrates an end view of a portion of a book composed of sections and arranged generally in the modified manner illustrated in Figure 5.

In the drawing, particularly referring to Figures 1 to 3, the sample color card book is composed of individual sections, secured together by means of flexible binders indicated at 10, 11 and 12. Each section comprises a rigid, flat base member 13, made preferably of hard cardboard or similar material, and provided at its long edges with projecting reinforcing rails 14, made preferably of wood and which serve not only as reinforcing members for the cardboard, but also as spacers between the adjacent sections, and as room- 75 providing means for the sample tabs disposed between the reinforcing rails.

Arranged with each base member, and disposed symmetrically between the reinforcing rails 14, are semi-rigid backing members or 80 strips 15, preferably secured with their extreme edges to the edges of the cardboard piece of the base members between the rails, while their inner lower surfaces rest freely against the base member.

Arranged symmetrically and in pairs, there are provided in the backing members slots 16 designed for accommodating individual sample color tabs indicated at 17. These tabs are composed of a carrier member 85 90 95 100

18, having reduced ends 19 adapted to slip into slots 16. The broadened portion between the reduced ends is intended for limiting the movement of the tab relative to the 5 backing member.

Secured to each carrier member 18 by means of glue or other means is a sample support 20 in the form of a cardboard piece. Its outer or front face forms a base or support for a yarn sample 21, which is composed of a bundle of parallelly arranged strands of 10 yarn, the ends of which extend beyond the edges of the sample support 20. The yarn sample is secured to the support by means of 15 a thread 22 which is slung about the yarn at the edges of the support, so that the ends of the yarn form tassels, while the portion between the tassels adheres to the upper face of the sample support. The thread portion, 20 not in engagement with the yarn sample, is arranged at and attached to the back face of the sample support, which back face is glued to the sample support carrier 18.

From Figures 1, 2 and 3 it will be seen that 25 all sections of the book are constructed alike. Obviously, however, modifications may be incorporated, such as illustrated in Figure 4, where a portion of a section is shown, also composed of a base member 23, the longer 30 edges of which are reinforced by spacing rails 24, while between the rails is placed a backing member 25. The latter is provided with the usual slots 26 for receiving the sample carrier, but in addition to these slots there are 35 provided windows 27 intended for exposing the elongated, reduced end 28 of sample carrier 29. The other end of the latter is also reduced as indicated at 30, but is shorter than end 28, which end serves for the purpose of 40 applying thereon a plainly visible identification marking for each individual sample.

The construction of the sample tab is otherwise identical with that described in connection with Figure 1. There is again provided 45 a sample support 31 against which rests a yarn sample 32, the ends 33 of which form tassels and are held together by means of thread 34, which is slung around them, while its other portions are brought back to the 50 rear face of the sample support, with which face the latter is attached to the upper face of sample carrier 29.

The arrangement of the individual sections 55 shown in Figures 1, 2 and 3 is such that the end section I folds against the second section II in a way that reinforcing rails 14 abut with one another. The flexible connection 10 between these two sections is just wide enough 60 to permit such folding.

The next section III is connected with section II by a flexible portion 11 which is wide enough to permit folding of sections I and II against section III so that the back or lower 65 surfaces of section I abuts with reinforcing

rails 14 of section III. This arrangement is clearly seen in Figure 3.

Section IV is connected with section III by a still wider flexible member 12, which allows a group of sections connected at the right-hand side of the book (not shown) to fold against one another, and, in its folded position, to bear against section II of the left-hand folded section group, as clearly illustrated in Figure 3. These other sections, not shown in Figure 1, are connected in the following order of folding from the extreme right-hand end towards section IV: Section 70 V faces section VI, section VII abuts with its upper face the rear of section V, and is next to section IV when the book is unfolded. 75

Referring to Figures 5, 6 and 7, a modified book arrangement composed of similar sections is shown, in which two individual sections are adapted to fold face to face towards 80 one another. In this manner the book comprises section pairs, the reinforced faces of which abut with one another, while the back face of one section of one pair abuts with the back face of the adjacent section of the 85 next pair, whereby an accordion effect is produced. In Figure 5 there will be seen sections I', II', III', IV' and V'. Sections I' and II' are connected by a flexible member 35 which is sufficiently wide to permit the folding of 90 the two sections face to face. Between section II' and III' there is a flexible connection 36 which is very narrow, but permits the folding of the two sections back to back. Between sections III' and IV' is again a flexible member 37 of the same widths as that indicated at 35 and serving for the same purpose. Sections 95 IV' and V' are connected by a much wider flexible member 38, which is designed to accommodate four folded-up section pairs, arranged in left and right hand groups of 100 two pairs each. This arrangement may be clearly observed from Figure 7, illustrating a nearly folded section book, in which additional sections VI', VII' and VIII' are illustrated, (which were omitted in Figure 6).

The construction of each individual section, shown in Figures 5, 6 and 7 are identical with that explained in connection with Figures 1, 2 and 3, and serve for accommodating individual, exchangeable color sample tabs.

While in Figure 7 four pairs of sections are illustrated, it is self-evident that the number of sections or section pairs may be altered to suit various requirements, as for instance indicated in Figure 8 where one half of a larger book is shown, which is composed of a group of four pairs of sections, connected 120 similarly to the manner already explained, and provided with a correspondingly wider flexible section group connecting member, indicated at 39.

From the foregoing it becomes self-evident 130

that sample books of this kind may be provided with any number of sections, and may be folded either in the manner illustrated in Figures 1 and 2, or in the way shown in Figures 5 and 7. It is self-understood, moreover, that variations in the order of folding the sections may be incorporated, without altering the purpose for which this invention is designed.

10 Similarly the arrangement and construction of the individual sections may be altered, and particularly the forms of the backing member and the tabs may be changed to suit any desired requirements, and I therefore reserve for myself the right to incorporate such modifications or improvements in my invention, as may become advisable or desirable, without departing from the broad scope of my idea as defined by the annexed 20 claims.

I claim:

1. A sample card book of the class described, comprising a plurality of individual sections flexibly connected edge to edge with one another and adapted to form a continuous row of sections foldable to a book, each section comprising a relatively rigid base member reinforced at its long edges, a backing member provided between the reinforced edges of said base member and having a plurality of tab-receiving means, arranged in pairs.

2. A sample card book of the class described, comprising a plurality of individual sections connected edge to edge with one another and adapted to form a continuous row of sections foldable to a book, each section comprising a relatively rigid base member provided at its long edges with combination reinforcing and spacing means extending beyond one face of said base member, a backing member secured to said base member between said reinforcing means and provided with a plurality of sample tab receiving slots, arranged in pairs.

3. A sample card book of the class described, comprising a plurality of individual sections flexibly connected edgewise with one another and adapted to form a continuous row of sections foldable to a book, each section comprising a relatively rigid base member provided at its longer edges with combination reinforcing and spacing means extending beyond one face of said base member, and comprising rigid rails, a semi-rigid backing member attached with its edges to said base member between said rails and provided with a plurality of receiving slots, arranged symmetrically in pairs, adapted to accommodate and securely hold color sample tabs.

4. A sample card book of the class described, comprising in combination, a plurality of individual sample-carrying sections

65 fixedly but flexibly connected edgewise with

one another and forming a continuous row of sections foldable to a book, each section composed of a relatively rigid base member provided at its longer edges with combination reinforcing and spacing means in the form of rails and extending beyond the sample-attaching face of said base member, a semi-rigid backing member secured with its edges to said base member between said rails and provided with a plurality of symmetrically disposed slots, arranged in pairs, removable sample tabs in engagement with said slots and composed of a carrier member having reduced ends registering with said slots, a sample support attached to said carrier and a yarn sample secured to said sample support.

5. A sample card book of the class described, comprising in combination, a plurality of individual sample-carrying sections flexibly connected edgewise with one another and forming a continuous row of sections foldable to a book, each section composed of a relatively rigid base member provided at its longer edges with combination reinforcing and spacing means in the form of rails and extending beyond the sample-attaching face of said base member, a semi-rigid backing member secured with its edges to said base member between said rails and provided with a plurality of symmetrically disposed slots, arranged in pairs, removable sample tabs in engagement with said slots and comprising a carrier member having reduced ends in registry with said slots, a sample support attached with its back face to said carrier, between its reduced ends, a yarn sample secured to the front face of said support, and a means for securing said yarn sample to said support.

6. A sample card book, comprising a plurality of reinforced, individual sample-carrying sections, each section composed of a rigid base member, reinforcing spacers provided at the long edges thereof, a backing member disposed between said spacers, flexible connecting means provided between said sections, some of said connecting means being wider than the others, the wider connecting means permitting the folding of two sections face to face, while the less wide connecting means facilitate the folding of two adjacent sections back to back, whereby an accordion-like folding is effected.

7. A sample card book composed of a plurality of individual sample-carrying sections, each section composed of a rigid base member, reinforcing spacers provided at the long edges thereof, and a backing member disposed between said spacers; said sections connected with one another by flexible means in such a way as to facilitate the folding of the sections in pairs, groups of pairs and groups of groups.

8. A sample card book comprising a plu-

rality of reinforced individual sample-carrying sections flexibly connected with one another so as to fold together in accordion fashion, each section provided with a backing member arranged between the reinforcements of the section and equipped with a plurality of tab receiving-slots, arranged in pairs.

9. In a device for the purpose described, a book formed from a plurality of sections including end sections, and second and third intermediate sections, counting from the end sections towards the center of the book, each section comprising a relatively wide and long, stiff and flat base member, a pair of parallel, relatively narrow reinforcing members at both long edges of the base member and of greater thickness than the latter, extending beyond the inner face of the base member while being flush with the outer face or back of the latter, a backing member secured to said base member between said reinforcing members and provided with a plurality of carrier card receiving slots arranged in pairs, flexible connections provided between all sections and increasing in width from both ends towards the center and adapted to facilitate the folding of the sections from both ends towards the center into a book in the following manner: the end sections folding against the second sections with their respective inner faces facing one another and with their reinforcing members, extending beyond their faces, touching one another, the third sections folding with their inner faces against the backs of the end sections.

10. A color card book composed, in combination, of a plurality of flexibly interconnected, individual sections adapted to be folded to a book form, starting from both end sections towards the center, each section comprising a stiff, flat, elongated base member, a pair of reinforcing members disposed at both long sides of the base member and extending beyond the inner face thereof while being flush with the back face of the base member, a backing member secured to the inner face of said base member between said reinforcing members and provided with a row of slots arranged in pairs, and a cut-out in line with and adjacent to each slot pair, carrier cards removably associated with the slots of said backing member and comprising oblong strips having reduced ends adapted to engage and register with said slots, one of the reduced ends of the carrier cards being elongated to pass under and fill the said cut-out, a sample support secured with its rear face to each of said carrier cards and being shorter than the latter, a yarn sample, longer than said support, secured to the latter's front face and extending with its ends beyond the edges of said support, a thread looped around the extending ends of said yarn sample and having its ends attached to

the rear face of said sample support whereby the latter is secured to said carrier card.

In testimony whereof I herewith affix my signature.
